CLAIM

The ornamental design for a combined diamond painting sealer applicator and cap, as shown and described.

DESCRIPTION

FIG. 1 is a front perspective view of a combined diamond painting sealer applicator and cap, showing my new design;
FIG. 2 is a front view thereof;
FIG. 3 is a top view thereof;
FIG. 4 is a bottom view thereof;
FIG. 5 is a perspective view of its open state;
FIG. 6 is the front view of its open state;
FIG. 7 is the left side view of its open state; and,
FIG. 8 is the right side plan view of its open state.
The dashed broken lines depict portions of the combined diamond painting sealer applicator and cap that form no part of the claim design.

1 Claim, 8 Drawing Sheets
